UNITED STATES PATENT OFFICE.

LLOYD C. NICHOLSON, OF BUFFALO, NEW YORK.

OVERLOAD DEFINITE-TIME-LIMIT RELAY.

Specification of Letters Patent. Patented Aug. 27, 1918.

1,277,249.

Application filed September 7, 1915. Serial No. 49,235.

To all whom it may concern:

Be it known that I, LLOYD C. NICHOLSON, a citizen of the United States, residing at Buffalo, in the county of Erie and State of New York, have invented certain new and useful Improvements in Overload Definite-Time-Limit Relays, of which the following is a specification.

My invention relates to a relay, and more particularly to an overload definite time limit relay.

One of the objects of my invention is the production of a relay of this type that will produce a certain definite motion in a certain definite number of alternations during which an overload current of greater value than a predetermined quantity remains in the circuit.

Another object of my invention is the production of a relay that may be used to record the number of alternations of current passing through it, and whereby a time record can be obtained of any flow of the alternating current by means of a stationary scale and a pointer or indicator co-acting therewith.

A further object is to provide a device of this character which will respond to a certain predetermined flow of alternating current 30 rent through its windings and thereupon cause a movable contactor to approach and touch a stationary contactor in a predetermined length of time and to return the movable contactor promptly to its zero position 35 after such flow of current decreases to less than the predetermined value.

Further objects are to provide a mechanism of this kind in which there are no contacts necessary to cause vibration of the armature; and to otherwise improve on devices of this type.

To these ends the invention consists in the novel arrangement of devices, in the novel arrangement of parts, and in the combination of elements and peculiar construction of parts, to be hereinafter described and particularly pointed out in the subjoined claims.

In the drawings,

50 Figure 1 is a side elevation of my improved relay showing one application of the same, the various devices being shown diagrammatically.

Fig. 2 is a side elevation of my improved 55 relay, a portion of the same being broken

away to better illustrate parts otherwise hidden.

Fig. 3 is a plan view.

Fig. 4 is an end elevation viewed from the left in Fig. 2. 60

Fig. 5 is a transverse section taken on line $a-a$, Fig. 2, the ratchet wheel and brake drum being shown in elevation.

Fig. 6 is a transverse section taken on line $b-b$, Fig. 2, the binding post through which 65 said line passes being shown in elevation.

Fig. 7 is a detached perspective view of one of the contactors of the device.

Fig. 8 is a fragmentary vertical section of 70 the same.

Fig. 9 is a longitudinal section through the outer end of the armature and parts connected thereto.

Referring now to the drawings in detail, like numerals of reference refer to like parts 75 in the several figures.

Reference being had to Fig. 1, 10 designates an alternating current generator having circuit wires 11, 12, connected thereto, said wires forming an electric circuit in 80 which are included solenoid-operated switches 13 by means of which said electric circuit is established and broken, the solenoid-operated switches being well known to the art and therefore it is not believed necessary to show or describe them in detail. 85

14 designates a relay which is connected with the circuit wire 11 by means of a series transformer 15. The relay has a stationary contactor 16 and a movable contactor 17, the contactor 17 being connected by a circuit wire 18 with one of the solenoids 19 controlling one of the switches 13, said solenoid being connected by a circuit wire 20 with the other solenoid 21. The 90 movable contactor 16 is connected with one pole of a battery 22 by a wire 23, the other pole of the battery being connected by a wire 24 with the last-mentioned solenoid. The circuit in which the solenoids are included therefore has a battery as a source 100 of electrical energy and may be termed a "control" circuit, and when the movable contactor 17 is brought into engagement with the stationary contactor 16 the solenoids 19, 21, are energized by the battery current a predetermined length of time after the electric circuit begins to deliver excess current, as for example, when the electric circuit is short circuited. It is of course 105

110

understood that the coil of the relay is energized by the secondary of the series transformer, as is well known in the art.

Reference being had to the relay, 25 designates a plate or base from which rise two pairs of standards or supports 26, 27, the pair of standards 26 being spaced from the pair of standards 27 and both pairs having a laminated soft iron core or magnet 28 extending therebetween, said core being horseshoe shaped and having an upright arm or pole held between each pair of standards or supports. The core or magnet 28 is wound with an exciting coil 29 connected to binding posts 30, 31, which are in turn connected to the source of alternating current, through the transformer 15.

Interposed between the two pairs of standards or supports 26, 27, directly above the poles of the horseshoe magnet is a pivoted armature 32 which is in close proximity to one pole 33, as at 34, but normally separated from the other pole 35, as at 36. The normal position of said armature is its uppermost position and it is held against an adjustable stop 37 secured to the top cross bar 38 connecting the upper ends of the standards 27. This adjustable stop is shown in the form of a screw passed down through the connecting bar 38 and bearing with its lower end against the upper face of the armature, as at 39, said screw being adjusted through said cross bar and being held in any adjusted position by a jam nut 40 threaded thereon and bearing against said cross bar. The armature is retained in its uppermost or normal position by an adjustable tension device 41 which comprises a coil spring 42 secured at one end to a screw 43 passed through the cross bar 38 and held in adjusted position by a nut 44 and jam nut 45, the opposite end of said spring being fastened to a stud 46 secured in the armature.

The armature 32 extends beyond the pole 35 of the magnet, and at its outer end carries a ratchet actuating device 47. This device comprises a dog 48 pivoted to the outer end of the armature, as at 49, and having an overhanging stop arm 50 adapted to bear against the upper face of said armature to prevent upward movement of said dog beyond a certain point. This dog is normally held in its uppermost position by a coil spring 51 having one end secured to said dog 48 and its other end secured to an L-shaped arm 52 extending upwardly and outwardly from the armature. The magnet 28, exciting coil 29, armature 32, and parts connected thereto and carried thereby I term "actuating mechanism" or "motor", which is adapted to actuate timing and controlling mechanism to be now described.

A pair of standards 53 is secured to the plate or base 25 and journaled in these standards is a shaft 54, said shaft having

secured thereto midway between the two standards 53 a ratchet wheel 55, and at each side of the ratchet wheel between the same and each standard or support 53 is a brake wheel or drum 56, said brake wheels or drums being secured to the shaft in any suitable manner. At one end of said shaft a pinion 57 is secured and this shaft extends through a boss 58 formed on one of the standards 53, said boss having a graduated dial 59 secured thereto and the projecting end of said shaft having an indicating finger 60 secured thereto. The dial is therefore held against movement while the indicating finger travels in a circular path over the graduated face of said dial. The ratchet wheel 55 is arranged in line with the dog 48 and is adapted to have its teeth engaged by said dog when the actuating mechanism or motor is placed in motion or, in other words, when the armature is attracted by the magnet.

The plate or base is provided with a fourth set of standards 61, through which a shaft 62 is passed, said shaft having a collar 63 secured thereto and bearing against the inner face of one of said standards. A tension spring 64 is placed around said shaft and has one end secured to said collar, as at 65, and its other end fastened to the opposite standard, as at 66. One of the standards 61 is provided with a boss 67 on its outer side to which a collar 68 is fastened, and extending from this collar is a stop arm 69. One end of said shaft 62 has a gear wheel 70 secured thereto which is in mesh with the pinion 57. Said gear wheel has the contactor 17 extending from the rim thereof, which by reason of its moving with said gear wheel I have termed the movable contactor. Said movable contactor is adapted to be brought into engagement with the contactor 16 rising from the plate or base 25, and which I have termed the stationary contactor. While said stationary contactor has movable parts, it is termed stationary for the reason that it is retained in stationary position on the plate or base 25. This stationary contactor comprises a base member 71 which is threaded into the plate or base 25, or otherwise fastened thereto, and a top member 72 pivotally secured to the base member, as at 73, said members having beveled contacting faces 74, 75, at a point beneath the pivot 73 so that member 72 may be swung on member 71 in one direction only, and in order to retain said top member in line with said base member a flat spring 76 is secured to said base member and extends upwardly therefrom with its upper end in contact with said top member.

Shaft 62 has rigidly secured thereto or formed thereon a stop device 77 which is adapted to normally bear against the stop arm 69, said stop device may be formed by

reducing the diameter of the shaft 62 and bending the same at a right angle, as at 78, and thence rebending the same at a right angle to said first right-angled portion, as at 79, to form a stop portion parallel with the shaft 62 and adapted to engage the underside of the stop arm 69. The stop device is retained in contact with the stop arm 69 by the coil spring 64 surrounding shaft 62.

80 designates flexible brakes secured to the top plate 81 connecting the upper ends of the standards 61, said flexible brakes being formed of steel and extending inwardly over the brake wheels or drums 56 so that they will engage said wheels to prevent retrograde movement of shaft 54 and the parts rotatable therewith during the upward movement of the armature 32. These brakes, or brake bands as they may be termed, are applied to the brake wheels or drums during the attracted or downward movement of the armature and therefore also prevent over-shooting of the ratchet wheel 55; that is to say, they prevent the ratchet wheel moving more than the distance it is intended the armature 32 shall cause it to move, which is one tooth for each downward stroke of the armature. When the armature 32 is in normal or elevated position, the flexible brakes 80 are out of contact with the brake wheels or drums.

The relay serves as a motor of the vibrating armature type. The passage of alternating current through the exciting coil 29 attracts the armature 32, drawing it downward until it rests against the pole piece 35 of the core or magnet 28. From the nature of alternating current, which gradually increases to maximum and then decreases to zero during each alternation, the force exerted on armature 32 is pulsating and pulsates with the frequency of the alternating current supplied to the coil 29. At each alternation of the alternating current, whose effective value is above a certain predetermined amount determined by the tension of the spring 42, armature 32 vibrates in synchronism with the alternations of such current. Therefore, at each alternation the dog 48 engages the ratchet wheel 55 and drives the same forward the distance of one tooth simultaneously therewith. The brake-bands 80 are applied to the brake-drums 56 and prevent the ratchet wheel 55 over-shooting or moving more than the distance which the dog 48 travels after engaging a tooth of said ratchet wheel. These brakes also hold the ratchet wheel against rotation while the armature moves upward and disengages the dog from said wheel so that there is no retrograde movement of said ratchet wheel by reason of the pressure of the dog against the teeth on account of the tension of spring 51. The intermittent rotation of the ratchet wheel 55

causes rotation of the shaft 54 and, through the medium of the pinion 57 and gear wheel 70, rotates shaft 62. The rotary movement of gear wheel 70 causes the movable contactor 17 to be brought into engagement with the stationary contactor 16 at the same time causing the stop device 77 to travel away from the stop arm 69.

The driving movement of shaft 62, which is that caused by the pinion 57, is resisted by the coil spring 64 around shaft 62. When the relay is inoperative, this spring returns the parts carried or actuated by shafts 54 and 62 to normal position, which is that in which the indicating finger 60 points to zero on the graduated dial 59; in which the stop device 77 bears against the stop arm 69; and in which the movable contactor 17 is at its greatest distance from the stationary contactor 16.

It is to be noted that the collar 68 to which the stop arm 69 is secured is rotatably adjustable on the boss 67 of the standard or upright 61. The stop arm, therefore, may be adjusted to cause the shaft 62 to have a greater or lesser movement so as to cause the movable actuator to travel through a longer or shorter path during the actuation of the vibrating armature motor.

The circumferential position of the stop arm 69 determines the zero point of the time limit of the relay and therefore the range of movement contactor 17 has to travel through before touching contactor 16. It is of course apparent that when the circumferential position of the stop arm 69 is changed it is desirable to change the position of the indicating finger 60 on shaft 54 so that it will point to zero on the graduated dial when the stop device 77 is in contact with the stop arm 69.

In the drawings I have shown meshing gear wheels to decrease the speed of shaft 62, and consequently that of the gear wheel 70 carrying the movable contactor 17, and in this way provide the relay with a longer maximum time limit. It is apparent that the principle of operation would not be departed from if the contactor 17 was mounted directly upon the ratchet wheel 55, but in such case the maximum time limit attainable would be considerably less than obtained by gearing down the motion of said ratchet wheel.

The stationary contactor 16 is made in two parts hinged together with one movable relatively to the other, since there is a rubbing motion produced between the same and the movable contactor 17, and by reason of hinging the upper part to the lower part, 125 good electrical contact is assured.

Assuming that the normal load current in the electric circuit, in Fig. 1, is ten amperes, and it is desired to switch off the circuit after a certain definite length of time 130

upon the occurrence of twenty amperes or more in the circuit, say two seconds after the current increases to twenty amperes or more. Assuming also that the ratio of the 5 series transformer 15 is ten to five amperes (ten amperes primary and five amperes secondary), ten amperes will flow in the secondary when twenty amperes flow in the primary. Under such conditions the spring 10 42, which holds the armature 32 elevated, is adjusted so that the armature will be attracted when ten amperes or more flow through the coil 29. Now assuming that the frequency of the alternating current is 15 twenty-five cycles per second or fifty alternations, immediately upon the occurrence of twenty amperes or more in the electric circuit, armature 32 will vibrate between the adjusted stop 37 and the pole 35 of the magnet in synchronism with the alternations in 20 this current. It will therefore make fifty complete strokes per second. Each stroke will drive ratchet wheel 55 forward the distance of one tooth, and the extent of rotation or speed of said wheel will therefore be fifty teeth per second. This motion is transmitted through gears to the movable contactor 17, and by properly positioning the stop arm 69 the movable contactor will 25 engage the stationary contactor 16 in a period of time corresponding to one-hundred strokes of the armature 32. When these contactors come together, the solenoids 19, 30 21, of the switches 13 are energized from the battery 22 and the switches are thereby immediately opened and the electric circuit disconnected, whereupon the flow of alternating current ceases and armature 32 remains in its normal or elevated position 35 40 against stop 37. At the same time the timing and controlling mechanism returns to its normal position through the action of which the stop device 77 engages the stop 45 arm 69, in which the indicating finger 60 points to zero on the graduated dial, and in which the movable contactor 17 is farthest from the stationary contactor 16.

In case the excess current above twenty 50 amperes does not continue to flow for one-hundred alternations, but for any reason decreases back to less than ten amperes in less time than is required to move the movable contactor 17 into engagement with the 55 stationary contactor 16, armature 32 ceases to vibrate and the mechanism returns to its zero position without opening the solenoid switches 13.

It is to be noted that the cross sectional 60 area of armature 32 is relatively small compared to that of the magnet or core 28, which causes the armature to be thoroughly saturated with magnetic flux at current values above a certain minimum, below which the 65 relay will not operate successfully. By rea-

son of the saturation of armature 32 at all working currents above a certain minimum, failure to operate by reason of extraordinarily heavy currents is obviated. For example,—if armature 32 is not sufficiently 70 saturated at ten amperes, then upon the occurrence of say thirty amperes in the coil the armature will be held down against the pole 35 and would not vibrate sufficiently to cause operation of the relay, but by making 75 this armature of relatively small cross sectional area, heavy currents in coil 29 do not produce this effect. This is an important advantage since the over-load current which can occur in an electric circuit may run up 80 to very high values.

By adjusting the brake-bands 80 so that they continuously rest upon the brake wheels or drums 56, or by removing the spring 64, a time record can be obtained of any flow 85 of alternating current by means of the stationary graduated dial, or any other scale and the indicating finger attached to the axle 54.

The dial or scale is, of course, to have one 90 division or graduation for each tooth of the ratchet wheel 55, hence the displacement of the indicating finger from zero will show the number of alternations of currents which has passed through the coils 29. It is of 95 course to be understood that the dial 59 and indicating finger 60 may be removed from the shaft 54 when the device is used otherwise than for ascertaining the number of alternations of current which has passed 100 through the coil 29, but the device is equally operative for all its purposes even though said dial and indicating finger are retained upon the shaft 54.

I have shown in the drawings a single 105 relay element for single phase circuits, but it will be clear to those skilled in the art that the device may be used in connection with multiple phase circuits, a relay element being used for each phase of the circuit; for example,—three relays would be necessary in a three phase circuit.

It will further be apparent that this invention may be modified in various ways without departing from the spirit of the 110 same or sacrificing any of the advantages thereof.

Having thus described my invention, what I claim is,—

1. The combination of an alternating current circuit, solenoid-operated switches in said circuit normally closing the same, a vibrating synchronous motor responding to a certain predetermined flow of alternating current through said circuit, a normally 120 open battery circuit including the solenoids of said switches, and means to close said battery circuit actuated by said vibrating motor.

2. The combination of an alternating cut 125

rent circuit, a switch normally closing said circuit, a vibrating electrically operated synchronous motor responding to a certain predetermined flow of alternating current through said circuit, a control circuit including a solenoid for actuating said switch, and a pair of contactors relatively movable and adapted to be brought into contact with each other by said electrically-operated motor, 10 said contactors serving to establish current through said control circuit and energize said solenoid to actuate the switch and open the alternating current circuit.

3. The combination of an alternating current circuit, a transformer in said circuit, a vibrating-armature synchronous motor connected with the secondary coil of said transformer and adapted to be placed into action at a certain predetermined flow of alternating current through said transformer, and positively driven means actuated by said motor to break the circuit.

4. The combination of an alternating current circuit, of mechanism responding to a certain predetermined flow of alternating current through said circuit and adapted to produce a certain definite motion in a certain definite number of alternations within said circuit during which an overload current of greater value than the predetermined quantity remains in the circuit, and positively driven means for breaking the circuit by means of said mechanism after a predetermined number of current alternations.

35 5. A relay comprising an alternating current magnet, a pivotally secured armature adapted to vibrate synchronously with the alternations of said current, a dog pivotally secured to the free end of said armature, a ratchet wheel adapted to be engaged by said dog, and means to prevent over-shooting of said ratchet wheel and also to prevent retrograde movement of said ratchet wheel upon idle or return movement of said dog.

45 6. A relay comprising an alternating current magnet, a vibrating armature associated therewith, a shaft mounted for rotatable movement, a ratchet wheel secured to said shaft, a dog on said armature actuating said ratchet wheel, a brake drum on said shaft, a 50 brake band adapted to engage said brake drum during the attracted movement of said

armature, and means to establish a controlling circuit actuated by said shaft.

7. A relay comprising an alternating current motor, a shaft rotatably mounted, a prime mover secured to said shaft and actuated by said motor, a pinion on said shaft, a brake drum on said shaft, a brake band normally out of contact with said brake drum and adapted to act against the latter when said prime mover is actuated by said motor, a second shaft, a gear on said second shaft meshing with said pinion, means to hold said second shaft in a certain position circumferentially, an electrical contactor movable with said gear, a fixed electrical contactor against which said first-mentioned contactor is adapted to engage when said second shaft is rotated through a certain range of movement, and means to return said second shaft to normal position when it ceases to rotate.

8. A relay comprising an electric motor, a rotatable shaft, means actuated by said motor for rotating said shaft, a circumferentially adjustable stop, a stop device rotatable with said shaft and adapted to normally bear against said stop, an electrical contactor caused to travel through an arc of a circle during the rotation of said shaft, an electrical contactor against which said first-mentioned contactor is adapted to engage to establish a controlling circuit, and means to reverse the movement of said shaft so as to return said stop device to normal position in contact with said circumferentially adjustable stop.

9. A relay comprising an alternating current magnet, an armature adapted for movement toward and from said magnet with the alternations of said current, a controlling mechanism including a ratchet wheel, a dog pivotally secured to the outer end of said armature and having an overhanging stop adapted to bear against the upper face of said armature, said dog being adapted to actuate said ratchet wheel during the attracted movement of said armature, and a spring tending to draw said dog upwardly and retain said overhanging stop in contact with said armature.

In testimony whereof I affix my signature.
LLOYD C. NICHOLSON.
